UNITED STATES PATENT OFFICE.

THOMAS CLARENCE HEISEY, OF NEWARK, OHIO, ASSIGNOR TO A. H. HEISEY AND COMPANY, OF NEWARK, OHIO.

DESIGN FOR A CANDLESTICK.

Application filed March 23, 1926. Serial No. 17,019. Term of patent 14 years.

To all whom it may concern:

Be it known that I, THOMAS CLARENCE HEISEY, a citizen of the United States, residing at Newark, in the county of Licking and State of Ohio, have invented a new, original, and ornamental Design for Candlesticks, of which the following is the specification, reference being had to the accompanying drawing, forming a part thereof.

The figure is a perspective view of a candlestick showing my new design.

I claim:

The ornamental design for a candlestick, as shown.

T. CLARENCE HEISEY.
